UNITED STATES PATENT OFFICE

HARRY MUNSON, OF WANTAGH, NEW YORK, ASSIGNOR TO VAN KANNEL REVOLVING DOOR COMPANY, OF NEW YORK, N. Y., A CORPORATION OF NEW JERSEY

SPEED REGULATOR FOR REVOLVING DOORS

Application filed March 6, 1931. Serial No. 520,746.

This invention relates to revolving doors, and comprehends an improved means for controlling the speed of rotation of the door so as to prevent turning of the same above a predetermined maximum, thereby avoiding spinning of the door and the disadvantages resulting therefrom.

The present invention broadly aims to provide a hydraulic speed regulator for revolving doors, in which use is made of the retarding action of the flow of oil or an equivalent incompressible fluid through a passage and against a part movable by the door to control the speed of rotation thereof.

More particularly, the invention resides in a hydraulic speed regulator for revolving doors, in which a reciprocating means operatively connected with and actuated by the revolving door is employed for displacing an incompressible fluid which sets up a retarding action upon the speed of rotation of the door when said speed reaches a predetermined maximum, the invention further residing in means for regulating the speed of displacement so that the maximum speed of rotation of the door may be varied.

The invention further resides in the provision of a hydraulic speed regulator or controller for revolving doors, by virtue of which the revolving speed is continuously under control and the retarding force gradually increased as attempts are made to spin the door.

As a further feature, the invention embodies in a hydraulic speed regulator or controller for revolving doors, having reciprocating plungers, a construction which insures against leakage of the fluid past said pistons or plungers, thereby avoiding loss of efficiency and insuring a proper functioning of the device at all times.

As a still further object, the invention contemplates a hydraulic speed regulator in which the resistance to the rotation of the door at any possible speed, is smoothly increased or decreased, thus avoiding intermittent functioning of the door.

Other objects reside in the provision of a hydraulic speed regulator for a revolving door which is comparatively simple in its

construction, capable of economic production and incorporation in the door structure and which is thoroughly reliable and highly efficient in its purpose.

With the above recited and other objects in view, reference is had to the following description and accompanying drawings, in which there is exhibited one example or embodiment of the invention, while the claims define the actual scope of the same.

In the drawings:

Figure 1 is a top plan view of the regulator connected with the center support of a revolving door.

Figure 2 is a sectional plan view thereof taken approximately on the line indicated at 2-2 in Figure 3.

Figure 3 is a vertical sectional view taken approximately on the line indicated at 3-3 in Figure 1.

Figure 4 is a side view with parts broken away and shown in section to disclose the underlying structure.

Referring to the drawings by characters of reference, A designates the wings of a revolving door which are carried by the central support B extending upwardly therefrom, and which central support is secured to a bearing C which bears upon an overhead support D, with respect to which the central support and bearing C are adapted to rotate.

In the present instance, the overhead support D is fashioned to provide a closed casing 5 provided with a pair of spaced cylinder portions 6 and 7, each having a closed end 8 and an open end which communicates with the casing 5. A by-pass or conduit 9 establishes communication between the cylinder portions 6 and 7 adjacent the outer closed ends thereof, and said by-pass is formed with any suitable means 10 for regulating the effective size of the by-pass or conduit. As illustrated in the present instance, the means 10 includes a plug 11 intersecting the by-pass 9 and formed with an aperture 12 coinciding with the bore of the by-pass. The plug 11 is provided with an axially threaded bore 13 which intersects the aperture 12, and a screw 14 is adjusted in the

95

100

threaded bore to regulate the effective size of the aperture 12. A piston or plunger 15 is mounted for reciprocatory movement within each of the cylinders 6 and 7, and each 5 piston is connected by a connecting rod 16 with a crank 17, the said cranks 17 being respectively formed on crank shafts 18 and 19 which are journaled for rotation on axes parallel to the central support B, which shafts 10 project upwardly through and above the casing 5 and have secured thereto pinions 20 and 21. The bearing C is fashioned to provide a gear 22 which meshes at substantially diametrically opposite points with the pinions 20 and 21 so that turning movement of 15 the central support B imparts turning motion to the pinions 20 and 21, their shafts 18 and 19, and hence through the cranks 17 and connecting rods 16, effects simultaneous reciprocations of the piston 15 in opposite directions within the cylinders 6 and 7. The casing 5, including the cylinders 6 and 7 and the by-pass 9, is filled with an incompressible fluid E, such as oil or its equivalent, which 20 may be supplied thereto through the tapped bores 24 or threaded bosses 25 which are respectively closed by the plugs 26 and closure caps 27.

In operation, the revolving of the door sets 30 up reciprocations of the pistons 15 simultaneously in opposite directions to move the fluid through the by-pass 9 and aperture 12 alternately in opposite directions corresponding with the movement of the pistons 35 15 in the cylinders 6 and 7. Obviously, this offers some resistance to the turning of the door at all times, but it is apparent that due to the restricted size of the by-pass, the resistance gradually increases with the speed 40 of rotation of the door so that the device in effect operates to prevent turning of the door above a predetermined maximum speed, which may obviously be varied by the adjustment of the screw 14. The device also 45 acts to positively preclude spinning of the door and brings the same to a stop more readily after the same is relieved of its moving force. In other words, through the medium of the device thus described, users of 50 the door are forced to turn the same at a more nearly uniform speed after the initial inertia has been overcome and are positively precluded from rotating the door above a predetermined maximum.

55 It will also be observed that due to the position of a plurality of circumferentially spaced pinions engaging with the gear on the central support, the checking or retarding action is imparted thereto at relatively different points so as to render the same more even and uniform in its application, thereby avoiding an intermittent checking action which would have the effect of rendering the door jerky in its movement. By virtue of the 60 complete filling of the casing with the fluid 65

E, it is apparent that leakage between the piston and cylinder walls is avoided and, hence, a proper functioning of the controlling device is insured at all times without the necessity of frequent fillings or adjustments. 70

While there has been illustrated and described a single and preferred embodiment of the invention, no limitation is intended to the precise structural details herein exhibited, as it is to be clearly understood that variations and modifications which properly fall within the scope of the appended claims 75 may be resorted to when desired.

What is claimed is:

1. In combination, a revolving door and a hydraulic speed regulator therefor including an overhead support for the door fashioned to provide a closed casing filled with an incompressible fluid, means operable by rotation of the door for moving the fluid in opposite directions within said casing and means intercepting the movement of the liquid to prevent its movement beyond a predetermined maximum whereby to limit the speed of rotation of the door. 80

2. In combination, a revolving door and a hydraulic speed regulator therefor including an overhead support for the door fashioned to provide a closed casing filled with an incompressible fluid, means operable by rotation of the door for moving the fluid in opposite directions within said casing and means intercepting the movement of the liquid to prevent its movement beyond a predetermined maximum whereby to limit the speed of rotation of the door, said intercepting means being adjustable to vary the maximum rate. 95

3. In combination, a revolving door and a hydraulic speed regulator therefor including an overhead support for the door fashioned to provide a closed casing filled with an incompressible fluid, means operatively connected with the revolving door for displacing the fluid and means for regulating the speed of displacement of said fluid by said first means. 100

4. In combination, a revolving door and a hydraulic speed regulator therefor including an overhead support for the door fashioned to provide a closed casing filled with an incompressible fluid, reciprocatory means operatively connected with the revolving door for displacing the fluid and means for regulating the speed of displacement of said fluid by said first means. 110

5. The combination with a revolving door, of a device for supporting and controlling the speed of rotation of said door including a member containing an incompressible fluid confined therein for limited movement, means operable by rotation of the door for moving said fluid and means for limiting the speed of movement of the fluid to con- 125

stantly retard the movement of the door and to limit the maximum speed thereof.

6. The combination with a revolving door, of a device for supporting and controlling the speed of rotation of said door including a member containing an incompressible fluid confined therein for limited movement and means operable by the rotation of the door for moving said fluid to permit of and retard the speed of rotation of the door and means for limiting the movement of the liquid to a predetermined maximum.

7. The combination with a revolving door, of a device for supporting and controlling the speed of rotation of said door including a member containing an incompressible fluid confined therein for limited movement and means operable by the rotation of the door for moving said fluid to permit of and retard the speed of rotation of the door and means for limiting the movement of the liquid to a predetermined maximum, said latter means being adjustable to vary said maximum speed.

25 8. The combination with a revolving door, of a combined speed controlling device and support for said door including a member defining a bearing for the door and forming a pair of spaced cylinders each having a closed end and an open end, a closed casing with which the open ends of the cylinders communicate, a by-pass establishing communication between the cylinders adjacent the closed ends, a pair of pistons mounted and connected for reciprocations simultaneously in opposite directions within said cylinders and an operative connection between said pistons and the door for effecting reciprocation of the pistons upon rotation of the door.

40 9. The combination with a revolving door, of a combined speed controlling device and support for said door including a member defining a bearing for the door and forming a pair of spaced cylinders each having a closed end and an open end, a closed casing with which the open ends of the cylinders communicate, a by-pass establishing communication between the cylinders adjacent the closed ends, a pair of pistons mounted and connected for reciprocation simultaneously in opposite directions within said cylinders, an operative connection between said pistons and the door for effecting reciprocation of the pistons upon rotation of the door and means for varying the size of said by-pass to regulate the maximum speed of rotation of the door.

65 10. A revolving door including a center spindle, a bearing member secured to the upper end of the spindle to turn therewith, a member fashioned to provide an overhead support upon which the bearing member bears for rotation, said support being further fashioned to provide a closed casing having spaced cylinder portions each having a closed

end and an open end, the open ends of the cylinders communicating with the casing and a by-pass portion establishing communication between the cylinder portions adjacent their closed ends, a piston mounted to reciprocate in each cylinder, crank shafts to which the pistons are connected, gearing coupling the spindle bearing member and crank shaft for actuating the pistons upon rotation of the spindle and an incompressible fluid completely filling the casing
